UNITED STATES PATENT OFFICE.

VICTOR E. EDWARDS AND PAUL B. MORGAN, OF WORCESTER, MASSACHUSETTS, ASSIGNORS TO THE MORGAN CONSTRUCTION COMPANY, OF SAME PLACE.

APPARATUS FOR HANDLING METAL BARS.

SPECIFICATION forming part of Letters Patent No. 628,528, dated July 11, 1899.

Application filed June 7, 1897. Serial No. 639,671. (No model.)

To all whom it may concern:

Be it known that we, VICTOR E. EDWARDS and PAUL B. MORGAN, citizens of the United States, residing at Worcester, in the county of Worcester and State of Massachusetts, have invented a new and useful Improvement in an Apparatus for and System of Handling Metal Bars, of which the following is a specification, reference being had to the accompanying drawings, forming a part of the same, in which—

Figure 1 represents in plan view an apparatus for handling metal bars as they are delivered from the rolls of a rolling-mill, said apparatus embodying our invention and illustrating our improved system of handling metal bars, including the successive processes of straightening, cooling, distributing into selected pockets, withdrawing from the several pockets and cutting into determined lengths, and delivering the finished product from the cutting mechanism upon a car or truck. Figs. 2 and 3 are respectively side and end views of the cutting mechanism and conveyer for delivering the bars when cut to the car or truck. Fig. 4 represents, on a larger scale and in sectional view, a portion of the cooling and straightening bed, the pockets for receiving the bars, and the transferring mechanism for delivering the bars into the several pockets, the section being taken on line 4 4, Fig. 1. Fig. 5 is a fragmentary sketch showing one of the rocking shafts with radial arms employed for maintaining the bars at different elevations on the cooling-bed; and Fig. 6 is a sectional view on line 6 6, Fig. 5.

Similar letters refer to similar parts in the different figures.

The objects of our invention are to provide an apparatus by which metal bars of various dimensions constituting the product of the reducing-rolls of a rolling-mill are straightened, cooled upon a cooling-bed, and distributed to any one of a series of pockets, from which they are withdrawn and cut into determined lengths and delivered from the cutting mechanism upon a car or truck; and these objects we attain by the apparatus which is shown and the operation of which is illustrated by the accompanying drawings

and is described in the following specification and particularly set forth in the annexed claims.

Referring to the accompanying drawings, A denotes a trough provided with a series of 55 positively-driven feed-rolls A', the peripheries of which project through openings into the trough A and serve to convey the metal bar as delivered from the reducing-rolls to a V-shaped trough A², preferably located upon a 60 higher level than the reducing-rolls, the trough A being inclined for that purpose. The metal bar when delivered upon the V-shaped trough A² is straightened by a straightening mechanism comprising a car A³, upon 65 which is mounted a gripping mechanism which seizes the forward end of the bar and holds it from longitudinal movement, while the rear end of the metal bar is seized by a gripping mechanism A⁴, pivotally connected 70 by links A⁵ with a reciprocating cross-head A⁶, which is attached to a piston inclosed within a steam-cylinder A⁷, by which the gripping mechanism A⁴ is moved back, thereby drawing the metal bar straight and into a 75 direct line between the car A³ and the cross-head A⁶, the pivotal connection between the gripping mechanism A⁴ and the cross-head A⁶ allowing the former to move sidewise in order to carry the metal bar from the V-shaped 80 trough A² over an inclined bed B. The straightening mechanism forms no part of our present invention, it having been fully shown and described in the application for Letters Patent of the United States filed by 85 said Edwards May 4, 1896, Serial No. 590,126.

The inclined bed B constitutes the first section of the cooling apparatus, upon which the bars are cooled preparatory to their being deposited in pockets, from which they are withdrawn to be cut into determined lengths, as hereinafter set forth. The section B of the cooling-bed consists of a series of rigid inclined skids B', upon which the bars are delivered from the straightening mechanism. 90 Between the skids B' are journaled a series of rocking shafts B², parallel with the skids and having radial arms B³ B⁴ extending therefrom. The arms B³ on each of the shafts B² are arranged in a plane at right angles with 95 100

the plane of the arms B⁴ upon the same shaft, and each series of arms are also arranged in straight horizontal rows extending lengthwise the bed B.

5 The rocking shafts B² are each provided with an arm B⁵, pivotally connected with a reciprocating rod B⁶, which is actuated by a piston inclosed in a steam-cylinder B⁷, by which the rocking shafts B² are simultaneously rocked back and forth one-quarter of a revolution at each movement of the reciprocating rod B⁶, carrying the series of radial arms B³ and the series of radial arms B⁴ alternately into a vertical position with their ends 10 projecting a short distance above the inclined skids B', as represented by the arm B³, Fig. 6, so that the arms which extend in a vertical position will form a row of dogs arranged in a straight horizontal line in order to hold the 15 bars from sliding down the inclined skids B'.

The horizontal rows of the arms B³ alternate with the rows of arms B⁴, so that the rocking motion of the shafts will allow the bars lying on the skids B' to move by gravity successively 20 down the inclined skids from one row of arms to the next lower row of arms until they are 25 finally delivered at the lower end of the bed B to the next section of the cooling apparatus.

The straightening mechanism and the bed 30 B are supported by a framework B⁹, Fig. 4, which is preferably suspended from overhead in order to leave the space beneath the supporting-frame B⁹ entirely clear for the remaining portion of the cooling apparatus, 35 which may be extended beneath the straightening mechanism and the bed B in order to economize space. The bars as they slide off the rigid inclined skids B' are caught upon a shelf D, having its upper surface D' inclined oppositely to the inclination of the skids B', so that a bar falling thereon will move by gravity beneath the bed B upon the second section of the cooling apparatus, which consists of a series of movable conveyors by 40 which the bars are carried in a horizontal plane a short distance and are then delivered upon a second series of similar conveyors, and so on until the bar is sufficiently cooled. As the time required for cooling varies with 45 the size of the bar in its cross-section, we provide means for varying the distance the bar is carried, according to the size of the bar, by forming a series of pockets under each series of conveyors and by throwing the appropriate series of conveyors out of action, 50 depositing the smallest bars into the first pocket and conveying the larger bars to the pockets farther removed. The pockets C are formed between upright standards C' C', 55 which also support horizontal shafts C², to which a series of sprocket-wheels C³ are attached. Pivoted upon the shafts C² at the side of each of the sprocket-wheels C³ are arms C⁴, each being provided with a circular 60 boss C⁵, over which and the sprocket-wheels C³ endless chains C⁶ are placed. The arms C⁴ are sufficient to span the space between 65

the upright standards C', and the free end of each of the arms C⁴ rests upon the upper end of the next adjacent standard C', so as to bring the upper side C⁷ of each of the chains C⁶ in a horizontal position, thereby forming a bridge across each of the pockets C. Each of the shafts C², which supports an endless chain C⁶, carries a ratchet-wheel C⁸, by which the shafts C² are simultaneously rotated with an intermittent motion by means of the pawls C⁹, which are carried upon the levers C¹⁰, pivotally connected at their free ends with a reciprocating rod C¹¹, which is actuated by a piston inclosed in a steam-cylinder C¹². Each of the arms C⁴ is provided with a horizontal flange C¹³, which supports the upper portion of the endless chain and sustains the weight of the bars. At the lower 85 end of the inclined shelf D is a hinged gate D², across which the bars slide upon the first series of conveyer-chains, thereby allowing the bars to be intercepted and deposited into a supplemental pocket D³ by raising the gate, 90 as shown by the broken lines D⁴. The intermittent motion of the first series of chains conveys the bars across the first pocket and delivers them upon the next series of chains spanning the second pocket, and so on until 95 it is desired to deliver the bars into one of the pockets. To accomplish the delivery of the bars, the series of arms C⁴ over any selected pocket are raised, as represented by the left-hand bar C⁴, Fig. 4, thereby allowing 100 the bars to fall into the pocket lying beneath the raised arms.

At one end of the pockets C and transversely thereto is a track F, having a truck F', carrying a motor F², a cutting mechanism F³, 105 a pair of feed-rolls F⁴, and a capstan F⁵, with intermediate mechanism, which is thrown into operative connection with the motor by means of the lever-handle F⁶. At the rear of the cutting mechanism F³ are a series of endless belts 110 F⁷, carried upon wheels F⁸, mounted upon parallel shafts F⁹ and F¹⁰. The shaft F⁹ is actuated by means of gears F¹¹, which connect it with one of the shafts C² and cause the upper side of the belts F⁷ to travel in the 115 direction of the arrow 1 and deliver a bar placed thereon upon an inclined table F¹², from which they slide by gravity upon a car F¹³ upon a track F¹⁴.

In operation the truck F' is moved along 120 the track F opposite the pocket containing the bars to be cut. A rope with one end attached to the capstan is wound around the end of the rod, and the capstan is set in motion to draw the end of the rod up to the feed-rolls F⁴, by which it is projected through the cutting mechanism until its forward end strikes a stop F¹⁵, adjustably attached to a trough F¹⁶, which is provided with a hinged bottom F¹⁷. When the bar has been severed 130 by the cutting mechanism, the hinged bottom F¹⁷ is opened, allowing the bar to fall upon the belts F⁷, by which it is delivered to the car F¹³.

The upper portion of each of the endless belts F⁷ is supported by a platform F¹⁸, which sustains the weight of the bars and prevents the sagging of the chain under the weight of the bar.

The operation of our improved apparatus is as follows: Each bar as delivered from the reducing-rolls of the mill is conducted to an elevated straightening mechanism by an inclined conveyor consisting of the trough A and feed-rolls. From the straightening mechanism, which may be of any known construction, the bar is placed upon a series of rigid inclined skids arranged in a uniform plane and is held by gravity against the first row of vertical arms which project above the plane of the skids, and as the row of arms are disposed in a straight line the hot metal bar will be preserved in a straight line. The rocking of the shafts carries the arms B³ and B⁴ alternately below the surface of the skids and allows the bars to move by gravity down the skids B' from one row of arms to the next lower row until the bars fall one by one from the skids B' upon the inclined shelf D. The opening of the gate D² allows any unmerchantable bars to fall into the supplemental pocket D³, while the closing of the gate D² will cause the bars to pass onto the conveyer-chains constituting the second section of the cooling-bed. The bar is permitted to travel upon the second section of the cooling-bed until it has become sufficiently cool, when one of the series of arms C⁴ is raised and the bar dropped into one of the pockets C, the bars of smaller cross-section falling earlier into the pockets and those of larger cross-section being carried a greater distance and being deposited in pockets farther removed.

What we claim as our invention, and desire to secure by Letters Patent, is—

1. In an apparatus for handling metal bars, the elevated straightening mechanism and an elevated inclined section of a cooling-bed in combination with a series of pockets and conveying mechanism located beneath said inclined section of the cooling-bed and forming the second section of the cooling apparatus, substantially as described.

2. The combination with a series of inclined skids forming the first section of a cooling-bed of a series of rocking shafts provided with radial arms arranged in horizontal rows and in two different planes and means for rocking said shafts whereby the arms in each plane are alternately brought into position to check the sliding movement of the bars over said skids, substantially as described.

3. In an apparatus for handling metal bars, a cooling-bed consisting of two sections, the first of said sections having means for straightening the heated bars and comprising a series of rigid skids upon which the bars are delivered from the straightening mechanism and the second of said sections consisting of movable conveyers upon which the bars are delivered from the first section, said con-

veyers being arranged in successive series, whereby the bars are delivered from one series to the next succeeding series, and means for throwing each of said series of conveyers out of action, whereby the bars are moved varying distances, substantially as described.

4. In an apparatus for handling metal bars, the combination of means for straightening the heated bars, a series of rigid inclined skids upon which the bars are delivered from the straightening mechanism, means for checking the movement of the bars over said inclined skids at stated intervals, whereby the bars are given a step-by-step movement, movable conveyers upon which the bars are delivered from said inclined skids, said conveyers being arranged in successive series by which the bars are delivered from one series to the next succeeding series, and means for throwing each series out of action, whereby the bars are moved varying distances, substantially as described.

5. In an apparatus for handling metal bars, the combination of means for straightening the heated bars, movable conveyers arranged in successive series, by which the bars are delivered from one series to the next succeeding series, a series of pockets to receive the bars arranged beneath and corresponding with the series of movable conveyers and means for throwing each of said series out of action, whereby the bars are moved varying distances and deposited in said pockets, substantially as described.

6. In an apparatus for handling metal bars, the combination of the following instrumentalities, viz: means for straightening the bars as they are delivered from the rolling-mill, a series of rigid skids or supports upon which the bars are delivered from the straightening mechanism, movable conveyers upon which the bars are delivered from said skids arranged in successive series and adapted to move the bars by a broadside movement, a series of pockets arranged beneath said movable conveyers, means for throwing each series of movable conveyers out of action, whereby the bars are moved varying distances and deposited in said pockets, a track extending transversely by the ends of said pockets and a cutting mechanism movable on said track, substantially as described.

7. The combination with the inclined section of the cooling-bed and a series of conveyers located in a lower plane than said inclined section, of a shelf having an inclined surface placed beneath the edge of said cooling-bed to receive the bars by gravity and conduct them to the conveyers, substantially as described.

8. In an apparatus for handling metal bars the series of endless chains with their upper surfaces in the same horizontal plane, means for imparting a motion to the chains in said series whereby a bar is transferred by a broadside movement from one series to the next succeeding series, substantially as described.

9. The combination with a series of pockets of conveying mechanism consisting of a series of sprocket-wheels, means for rotating said sprocket-wheels, endless chains carried by said sprocket-wheels with their upper surfaces in the same horizontal plane, whereby a bar is transferred from one series of said chains to the next succeeding series and means for raising each of said chains out of a horizontal plane, substantially as described. 5
10. The combination with a series of pockets of conveying mechanism consisting of a series of sprocket-wheels, means for actuating the same, arms pivoted at one end concentrically with said sprocket-wheels and endless chains carried by said sprocket-wheels and the free ends of said arms, and means for supporting said arms across said pockets, substantially as described. 15
11. The combination with a series of pockets, of a track placed transversely to said pockets and at the end thereof, a truck capable of being moved along said track, cutting mechanism mounted on said truck, a feeding mechanism mounted on said truck by which the bar is fed to said cutting mechanism and means for operating said feeding and cutting mechanisms, substantially as described. 20
12. The combination with a series of pockets of a track placed transversely to said pockets and at the end thereof, a truck capable of being moved along said track, a cutting mechanism mounted on said truck, feed-rolls by which the bar is fed to said cutting mechanism and a motor operatively connected with said feed-rolls and said cutting mechanism, substantially as described. 25

13. The combination with a series of pockets, a cutting mechanism, means for actuating said cutting mechanism, a feeding mechanism by which a bar is fed to said cutting mechanism, means for actuating said feeding mechanism, said cutting and feeding mechanisms being capable of being moved transversely to the ends of said pockets and a conveying mechanism by which the severed bars are taken from said cutting mechanism placed opposite either of said pockets and delivered to a common place of deposit, substantially as described. 40

14. The combination of an inclined conveyer by which a bar is conveyed from the rolls of a rolling-mill to a higher level and delivered upon a cooling-bed, an elevated inclined cooling-bed from which the bars are delivered by gravity, a receiving-shelf placed beneath the lower edge of said cooling-bed, a series of pockets located beneath said cooling-bed and means for transferring bars across said pockets, substantially as described. 45

15. The combination of an elevated inclined cooling-bed, a shelf having an inclined surface and placed beneath the edge of said cooling-bed, a hinged guide by which the bar is conducted from said shelf to a conveying mechanism and a conveying mechanism, substantially as described. 50

Dated this 27th day of May, 1897.
